UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

TRUNK-DRAWER HAT HOLDER.

Application filed July 7, 1923. Serial No. 650,193.

This invention relates to improvements in trunk drawer hat holders, more particularly adapted for holding men's hats.

Trunk drawers are not adapted to hold hats unless provided with a hat holder, and when thus provided, the space cannot very well be used for holding other articles due to the space occupied by the holder.

It is one of the objects of the present invention to overcome the above objectionable feature and provide a trunk drawer hat holder which is easily removable from the drawer to permit the use of the drawer for holding other articles.

15 A further object of the invention is to provide a trunk drawer hat holder in which the attaching parts of the holder will occupy but a minimum amount of space when the holder is removed.

20 A further object of the invention is to provide a trunk drawer hat holder which while of rigid structure presents a soft yielding surface for engagement with the hat carried thereby.

25 A further object of the invention is to provide a trunk drawer hat holder which is of simple construction, is strong and durable and is well adapted for the purpose described.

30 With the above and other objects in view, the invention consists of the improved trunk drawer hat holder and its parts and combinations as set forth in the claims, and all equivalents thereof.

35 In the accompanying drawing, in which the same reference characters indicate the same parts in all of the views:

Fig. 1 is a top view of a trunk drawer provided with the improved hat holder;

40 Fig. 2 is a vertical sectional view thereof taken on line 2—2 of Fig. 1;

Fig. 3 is a transverse sectional view taken on line 3—3 of Fig. 1; and

Fig. 4 is a sectional detail view thereof.

Referring to the drawing, the numeral 5 indicates a trunk drawer upon the inner opposite sides of which are mounted metal straps 6 having offset portions 6' to form between the offset portions 6' and the side portions of the drawer, sockets 7. Said sockets extend vertically to receive the downwardly extending portions 8' of the offset arms 8 mounted on the opposite sides of the oval shaped holder band 9. The holder band is constructed of metal and is formed

with upper and lower outwardly extending annular flanges 10 which reinforce the band and also provide an upper wide support for the hat mounted thereon. The horizontally extending portions 8" of the arms 8 form stops which engage the upper edges of the socket straps and position the arms with relation thereto. The band is covered on the inner side by a plush or other like material cover 11, and said cover extends over the annular flanges of the band and partly around the outer side of the band, and at said outer side the edges of the cover are folded inwardly around strips of tape or felt 12 which hold the cover on the band and also act as fillers to form cushions for the outer edge portions of the flanges.

As thus constructed, a hat inserted in the holder with its rim resting on the plush covered upper flange will be firmly held in position without liability of damage, and when it is desired to remove the holder, the holder is pulled upwardly to disengage the arms from the socket straps and the trunk drawer may be used for holding other articles as the socket members occupy but a minimum amount of space.

From the foregoing description, it will be seen that the trunk drawer hat holder provides a simple construction for holding hats in trunk drawers and which holder may be easily removed when desired.

What I claim as my invention is:—

1. The combination with a trunk drawer, of a hat holder therefor, comprising socket members mounted within and on opposite side portions of the drawer and having vertically extending sockets of elongated form in cross section, a flat holder band having an annular upper flange and offset and opposite downwardly projecting arms of elongated form in cross section which detachably extend into the socket members, and a yielding covering extending over the inner portion and upper flange of the holder band.

2. The combination with a trunk drawer, of a hat holder therefor, comprising strap socket members mounted within and on opposite side portions of the drawer, a metal holder band having an upper and a lower annular flange, offset arms mounted on the opposite sides of the holder band and projecting downwardly therefrom and removably into the sockets of the socket members, a yielding covering extending over the in-

ner face and annular flanges of the holder band, and a strip of tape extending around the outer side of the band and the covering between the flanges of the band.

- 5 3. A trunk drawer hat holder, comprising a pair of strap socket members, a holder band having an upper and a lower annular flange, offset arms mounted on the opposite sides of the holder member and projecting

10 downwardly therefrom and removably into

the sockets of the socket members, a yielding covering extending over the inner face and annular flanges of the holder band, and strips of tape extending around the outer side of the band and the covering between 15 the flanges of the band.

In testimony whereof, I affix my signature.

JULIUS RITTER, JR.
